United States Patent Office

Des. 179,436

Patented Dec. 25, 1956

179,436

DOOR LOCK MEDALLION PLATE OR SIMILAR ARTICLE

Richard H. Arbib, New York, N. Y., and Robert T. Curcuru, Birmingham, Mich., assignors to Signa-Craft, Inc., New York, N. Y., a corporation of New York

Application April 27, 1956, Serial No. 41,235

Term of patent 14 years

(Cl. D50—6)

Fig. 1

Fig. 1 is a front elevational view of a door lock medallion plate or similar article, showing our new design; Fig. 2 is a bottom plan view thereof; and Fig. 3 is a left end view thereof.

We claim:

The ornamental design for a door lock medallion plate or similar article, as shown.
